ROLLED FABRIC SUPPORT

Herbert Ferber, New York, N. Y.

Application January 26, 1937, Serial No. 122,401

2 Claims. (Cl. 242—55.2)

My invention relates to improvements in rolled fabric supports of the type which permits the goods to be readily unwound from the bolt for dispensing or display purposes.

5 The principal object of my invention is to provide a rolled fabric support of the character described, which will prevent damage to the bolt of goods supported thereon, which shall comprise relatively few and simple parts, thereby making 10 it easy to construct and assemble, which shall be rugged in construction, yet neat in appearance, which shall be easy to operate, highly efficient and a general improvement in the art.

Other objects of this invention will in part be 15 obvious and in part hereinafter pointed out.

The invention accordingly consists in the features of construction, combinations of elements, and arrangement of parts which will be exemplified in the construction hereinafter described, and of which the scope of application will be indicated in the following claims.

In the accompanying drawing, in which is shown one of the various possible embodiments of this invention,

25 Fig. 1 is a perspective view of a rolled fabric support embodying my invention;

Fig. 2 is a bottom plan view of the Fig. 1 form of device;

Fig. 3 is a cross-sectional view taken substantially on the line 3—3 of Fig. 2; and

30 Fig. 4 is a cross-sectional view taken substantially on the line 4—4 of Fig. 3.

Referring now in detail to the drawing, there is described a rolled fabric support constructed in accordance with my invention, comprising a base 10 constructed of any suitable rigid material such as wood. While in the drawing I have shown the base 10 as annular in shape, it is understood that any other satisfactory design for the base may be employed. Rotatably mounted upon 35 and spaced above the base 10 at a predetermined distance, is a platform 11. The said platform 11 may be made of material similar to that of the base and may be substantially equal in length to the diameter of the base 10, of sufficient width 40 to properly support a bolt of material B, and provided with rounded ends, as shown.

To aid in supporting the bolt B on the platform 11 and to cause the said bolt B to rotate with the said platform 11, I have provided an 45 upstanding flat member 15, preferably constructed of thin rigid non-twistable material, such for example as sheet metal, on the nature of approximately $\frac{1}{8}$ of an inch thick.

50 The bolt holding member 15 is preferably made

relatively wide, as shown, so that said member 15 will be prevented at all times from turning upon its axis within the bolt of material, which would render the device ineffective and cause damage to the goods. The height of the member 15 may 5 be made to suit the average size of the bolts of materials placed upon the support. When it is desired to dispense a portion of the goods from a rolled fabric, such as bolt B, the said bolt is placed on the member 15 so that the said member 15 either passes through the core C of the bolt B, or between two adjacent convolutions of the material near the core.

In rolled fabric supports of the character described, it is essential that there be no projecting portions or members on the surfaces of the member 15 or on the top surface of the platform 11 adjacent the member 15 to interfere or catch in the convolutions of the goods of the bolt B as it is slidably received on the member 15.

By my invention, I have provided a means for attaching the bolt holding member 15 to the rotatable platform 11, whereby the surfaces of the member 15 will be smooth from the top thereof down to and flush with the top surface of the platform 11. To accomplish this, I provide a slotted aperture 16 in the platform 11 to permit a portion of the member 15 adjacent the bottom end thereof to pass through said aperture 16, and extend below said platform a predetermined distance. The said projecting portion is then split approximately in half in a longitudinal direction with respect to the member 15, forming two extensions 15a and 15b which are then folded over in opposite directions, as clearly shown in Fig. 4, to overlie the bottom surface of the platform 11. The underside of the platform 11 may be recessed, as at 17 and 18, to cause the folded extensions 15a and 15b to be flush with the bottom surface of the platform 11. The means employed for preventing downward movement of the member 15 in the aperture 16 will soon become apparent.

For rotatably mounting the platform 11 on the base 10, I preferably employ a ball bearing device, 45 comprising a lower channelled annular member 20 suitably fastened to the base 10 by such means as screws 21, and an upper correspondingly channelled annular member 22. The member 22 is provided with an integral downwardly projecting shaft passing through an aperture 26 in the member 20, to maintain proper alignment between the ball bearing parts 20 and 22. To adjust the tension between the parts 20 and 22 on the balls 27, the base 10 is apertured as at 30 to 50 55

receive a downwardly projecting lip 31 adjacent the aperture 26, against which there is adapted to abut a nut 35 received on the threaded end 25a of the shaft 25. It is thus seen that when the nut 35 is tightened, the pressure on the balls 27 will be increased, and when the nut 35 is loosened the pressure will be lightened to cause freer rotation of the platform 11.

After the proper adjustment as above described has been made, the nut 35 may be retained in position by the insertion of a cotter pin 50 passing through the nut 35 and the shaft portion 25a. The nut 35 is preferably castellated to provide an entry for the cotter pin 50 at many points, and thereby avoid turning of the nut 35 after it has been properly adjusted.

The upper ball bearing part 22 is fixed to the platform 11 by any suitable means, such as round headed bolts 40 which are adapted at the same time to pass through the extensions 15a and 15b, to hold the member 15 fixed to the platform 11.

The handling of fabrics in connection with a device of the character described herein is usually accompanied by the releasing of loose goods particles, which tend to mix with the dust in the surrounding atmosphere and settle upon the mechanism, to impair its efficiency of operation. To overcome this disadvantage, I have provided the ball bearing part 22 with an overhanging wall 22a, which telescopes over the part 20 and serves as a guard to prevent lint and dust particles from entering the ball bearing channels.

It will thus be seen that there is provided a device in which the several objects of this invention are achieved, and which is well adapted to meet the conditions of practical use.

As various possible embodiments might be made of the above invention, and as various changes might be made in the embodiments

above set forth, it is to be understood that all matter herein set forth or shown in the accompanying drawing is to be interpreted as illustrative and not in a limiting sense.

Having thus described my invention, I claim 5 as new and desire to secure by Letters Patent:

1. A device of the class described comprising a base, a platform, an upstanding flat member adapted to have slidably received thereon a bolt of goods, means for rotatably mounting said platform on said base, and means for attaching said bolt holding member to said platform for rotation therewith, said last named means comprising a slotted aperture in said platform through which a portion of said member adjacent the bottom end thereof projects, said projecting portion being split longitudinally with respect to said member to form two extensions, each of said extensions being bent in opposite directions at an angle to said flat member to 15 overlie the bottom surface of said platform.

2. A device of the class described comprising a base, a platform, an upstanding flat member adapted to have slidably received thereon a bolt of goods, means for rotatably mounting said 25 platform on said base, and means for attaching said bolt holding member to said platform for rotation therewith, said last named means comprising a slotted aperture in said platform through which a portion of said member adjacent the bottom end thereof projects, said projecting portion being split longitudinally with respect to said member to form two extensions, each of said extensions being bent in opposite 30 directions at an angle to said flat member to 35 overlie the bottom surface of said platform, a portion of said platform bottom surface being recessed to receive said oppositely bent extensions.

HERBERT FERBER. 40
